CLAIM

The ornamental design for an electrical plug-in connector, as shown and described.

DESCRIPTION

FIG. 1 is a front perspective view of an embodiment of the electrical plug-in connector.

FIG. 2 is a rear perspective view of the electrical plug-in connector of FIG. 1.

FIG. 3 is a top-view of the electrical plug-in connector of FIG. 1.

FIG. 4 is a bottom-view of the electrical plug-in connector of FIG. 1.

FIG. 5 is a front-view of the electrical plug-in connector of FIG. 1.

FIG. 6 is a rear-view of the electrical plug-in connector of FIG. 1; and,

FIG. 7 is a left side-view of the electrical plug-in connector of FIG. 1 a right side-view being a mirror image thereof.

In the drawings, the broken lines are for the purpose of illustrating environment only and form no part of the claimed design.
